UNITED STATES PATENT OFFICE

RAYMOND O. BERKE, OF DENVER, COLORADO

DISPLAY DEVICE

Application filed May 14, 1928. Serial No. 277,433.

This invention relates to improvements in display racks of the type employed in stores for the vending of different articles such as peanuts and candy.

5 It is the object of this invention to produce a display rack that shall be specially well adapted for supporting and displaying peanuts or candy which is put up in sealed packages and which can be placed on the counter 10 or on the floor in such a position that the customers will have an opportunity to examine the goods and to remove such packages as they care to buy.

15 After the purchaser has selected his purchase he can then pay the attendant and in this way these devices become silent salesmen that greatly facilitate the operation of vending small articles of this class.

20 This invention, briefly described, consists in a base having an upwardly extending standard or support which is provided at spaced intervals with pairs of outwardly extending flanges to which supporting members are detachably secured. The parts are so constructed that the supporting members can 25 be rotated about the axis of the supporting standard so that a customer can have the opportunity of inspecting all the packages supported by the device without making it 30 necessary to move from one position.

The device may be made in several sizes, the smaller size being constructed so that it can be placed on the counter and the larger size so that it can be placed on the floor. A 35 large number of different kinds of articles can be displayed by this device, but they are particularly well adapted for use in displaying such goods as salted peanuts, candied peanuts and candies of all kinds.

40 In order to describe the invention so that its construction and operation can be readily understood, reference will now be had to the accompanying drawing in which the preferred embodiment thereof has been illustrated, and in which:

Fig. 1 is a vertical section through one of these display stands;

Fig. 2 is a section taken on line 2—2, Fig. 1;

Fig. 3 is a section taken on line 3—3, Fig. 1;

50 Fig. 4 is a section taken on line 4—4, Fig. 1;

Fig. 5 is a perspective view showing one of the supporting members removed and one of the packages in place thereon; and

Fig. 6 is a vertical section through a modified construction.

55 In the drawing numeral 1 indicates a base member which has a removable bottom closure 2 that is preferably covered with felt such as indicated by 3 for the purpose of preventing the scratching of the counters or the floors on which it may be supported. This base is preferably constructed so as to have a heavy cast iron member 5 of considerable mass which is provided with an outside covering 6 of sheet brass that is spun into a shape such as indicated on the drawing and applied to the outside of the casting so as to give the latter a finished appearance. The upper central portion of member 5 is provided with an opening 7 within which is rotatably mounted a supporting member 8. This member has a threaded plug 9 with which the lower end of the supporting standard 10 is threadedly connected. Member 8 is also provided with a downwardly projecting cylindrical plug 11, whose lower end is threaded as indicated at 12. Nuts 13 are secured to the lower end of plug 11 and are separated from the lower surface of member 5 by means of a washer 14. The member 8 is so adjusted that it can freely rotate and therefore the support 10 can be rotated whenever it is necessary to do so. Secured to the standard 10 at spaced intervals are pairs of attaching members 15 and 16. These members have outwardly extending flanges and downwardly extending hubs 17. The hubs are provided with openings for the reception of clamping screws 18 by means of which the supporting members are secured in place. The outwardly extending flange of member 15 is provided with a plurality of radial openings 19 for the reception of the ends of the straight supporting parts 20 of the supporting member. The flanges of member 16 are provided with openings 21 extending transversely thereof which are adapted to receive the end portions 22 of the support members. From Figure 5 it will be seen that the support members have a straight portion

20 which is integral with the upwardly extending inclined portion 23 that terminates in the upwardly extending end 22. Packages like those indicated by numeral 24 and 5 which are usually provided with perforated tabs 25 are threaded onto the straight part 20, after which the latter is inserted in one of the holes 19 in the flange of supporting member 15. The upwardly bent end 22 is 10 then inserted through one of the openings 21 and keeps the supporting arm from being accidentally removed. When small packages such as peanuts or candy packages are to be displayed by a device of this type, it is 15 possible to support quite a number of them on each of the supporting arms and as there may be a large number of these supporting arms, it is apparent that the display device will have a large capacity. The exact number 20 of supporting arms is immaterial as far as this invention is concerned and in the drawing eight such supporting arms have been shown, but a larger number may be employed if desired. The top of the support 25 10 is usually provided with an ornamental terminal 26 which gives it a finished appearance.

In the construction above described and shown in Figure 1, the supporting members 30 15 and 16 are separate from each other and are held in place on the support 10 by means of screws 18. With this construction it is necessary that the support 10 shall rotate in the base and for this purpose the construction 35 shown in Figure 3 has been provided. It is possible, however, to obtain substantially the same results by making the supporting members 15^a and 16^a integral in the manner shown in Figure 6, where these flanges have been 40 shown as connected by a central tubular member 27. When constructed as shown in Figure 6, the supporting members 15^a and 16^a with their connecting member 27 form a structure similar to an ordinary spool but the upper 45 flange 16^a is usually made of smaller diameter than the flange 15^a. These spools, instead of being clamped to the supporting bar 10, rest on a removable collar 28 that is held in place by means of a set screw 29. The supporting 50 arms are attached to the spools shown in Figure 6 in the same manner as described in connection with the embodiment shown in Figure 1.

Attention is called to the great ease with 55 which the supporting arms can be removed for the purpose of applying to them the goods to be displayed. It is only necessary to remove the arm 23 downwardly towards arm 20 sufficiently to remove the end 22 from the hole 60 21 in flange 16 after which the supported arm can be withdrawn.

I want to call particular attention to the specific construction of the spool and the supporting arms as this is of great importance 65 when considered in connection with the use to

which the device is to be put. The bags are provided with tabs 25 having openings through which the arm 20 extends. By having arm 20 substantially straight the bags can be readily put in place. If the free end of arm 20 were bent at right angles, it would be difficult to insert the arm into the holes in tabs 25. It is also desirable to hold the supporting arms against movement with respect to the spool and this is accomplished by providing hub 15^a with radial openings 19. If hubs 15 and 15^a had transverse holes like hubs 21, the supporting arms would swing about the spool which is undesirable. The supports also require the lower arm of the support to extend substantially horizontally so that the bags will remain where they are placed and at the same time a stronger support is formed if the upper arm 23 is inclined with respect to the lower arm as a triangular structure thereby obtained.

The specific embodiment described above is illustrative only of a type of display device and it is applicant's intention to claim this construction as broadly as the art permits as 90 it is evident that the same broad ideas can be embodied in structures that differ specifically from those illustrated on the drawing and description herein.

The idea of suspending bags whether perforated or not and whether or not provided with tabs 25 is comprehended in this invention.

It is, of course, possible to display and vend 100 similar goods by means of a center post provided with baskets, loops or rods on which bags can be supported or from which they can be suspended.

The rack may also have the name and price 105 cards supported in suitable places thereon.

In order to produce a more attractive display lamps may be placed near the center so as to be behind the bags and as the latter are made of translucent material they will make a better appearance especially in the evening.

A sign or any other advertising device may be fastened to the top of the support or attached to it so as to revolve or oscillate.

In order to signal the owner that a customer 115 is present a bell may be attached to the device so as to be sounded when a bag is removed.

From the above description it is believed 120 that the construction and the advantages of this invention will be readily understood by those skilled in the art and no further description will be attempted. Applicant, however, desires to again call attention to the fact that he contemplates making this display device in different sizes and that the one illustrated is not to be construed in a limiting sense, but 125 merely as an example of this type of device.

Having described the invention what is claimed as new is:

1. A display device comprising, a base, a supporting standard secured to the base and

extending vertically therefrom, said standard being provided with a spool having a pair of vertically spaced outwardly extending flanges, the lower flange of each pair having a plurality of radial openings, the upper flange having a corresponding number of correspondingly placed openings extending through the flange in the direction of its axis, and a removable supporting device comprising a substantially V-shaped member one side of which is substantially straight and has its end adapted to be inserted into one of the radial openings and having its other side bent and adapted to be inserted into the corresponding transverse opening in the other flange.

2. A display device comprising, a base, a supporting standard secured to the base and extending vertically therefrom, said standard being provided with a spool-like member, which consists of two circular disk-like flanges connected by means of a tubular hub member, one of said flanges having a plurality of radial openings, the other flange having a corresponding number of transverse holes, a supporting member for each pair of radial and transverse holes, said supporting members being substantially V-shaped, the end of one of the side members being substantially straight and adapted to be inserted into one of the radial openings and the other side having its end bent so as to adapt it to be inserted into the corresponding transverse opening in the other flange.

3. A display device comprising, in combination, a base, a vertical supporting standard secured at its lower end to the base, a collar adjustably secured to the standard, a spool rotatably connected with the standard above the collar and supported on the latter, said spool having vertically spaced circular flanges, the upper flange having a plurality of angularly spaced transverse holes, the lower flange having a plurality of radial sockets corresponding in number, and position with the holes in the upper flange and supporting devices attached to the flanges of the spool, said supporting devices each consisting of a wire bent intermediate its ends through an angle somewhat less than one hundred eighty degrees, whereby two angularly related arms are formed, one of said arms being substantially straight and adapted to enter a socket in the lower flange, the other arm having its end bent so as to lie substantially in the plane of the device and so as to make an angle of substantially ninety degrees with the other arm, said bent end extending through one of the holes in the upper flange whereby the supporting devices will resist a downward force.

In testimony whereof I affix my signature.
RAYMOND O. BERKE.
